Primary Examiner — W. A. Teddy Falloway*Assistant Examiner* — Yuan Yuan(74) *Attorney, Agent, or Firm* — Pearl Cohen Zedek Latzer Baratz LLP(57) **CLAIM**

The ornamental design for a hitting net as shown and described.

DESCRIPTION

FIG. 1 is a bottom-left perspective view of a hitting net showing our new design;

FIG. 2 is a top-right perspective view thereof;

FIG. 3 is a rear view thereof;

FIG. 4 is a front view thereof;

FIG. 5 is a left-side view thereof;

FIG. 6 is a right-side view thereof;

FIG. 7 is a top plan view thereof; and,

FIG. 8 is a bottom plan view thereof.

The broken lines shown in the drawings illustrate portions of the hitting net that form no part of the claimed design.
